land, Oreg., a corporation of Oregon

Application September 15, 1947, Serial No. 774,045

3 Claims. (Cl. 219—47)

1

This invention relates to improvements in high frequency electrical heating and has particular reference to the heating of dielectric bodies of large dimensions.

In heating dielectric bodies by high frequency alternating currents, the electrodes are arranged to produce a dielectric field including the body to be heated. If uniform heating of the body is desired, an electrode arrangement must be employed which will develop a reasonably uniform dielectric field in all parts of the body to be heated, and which is adaptable to the physical limitations of the apparatus with which it must be used. In heating thermosetting glue in a plywood press or scarf joint press, for example, it is convenient to utilize the metallic press platens as electrodes. When the length of each high frequency conductor from its coupling to the most remote extremity of its electrode is short in relation to the wave length of the energy radiation, satisfactory uniform heating of the glue may be accomplished.

However, with the use of larger presses and higher frequencies, difficulty has been experienced in obtaining uniform heating in all parts of the work in the press. It is found that variations in heating in different parts of the dielectric material are caused by the existence of different potentials at different points on the electrodes. When the conductor length is greater than a quarter wave length the standing wave produced has one or more fixed nodal points. At such nodes the potential on the conductor remains a minimum at all times and the heating effect in the dielectric adjacent such points is likewise small. Thus the occurrence of a standing wave produces uneven heating, and if one of the nodal points falls in the electrode very little heat is produced in the work at such point.

If the heating interval is sufficiently long, heat flow through the work will tend to equalize the temperature from point to point, but ordinarily the heat deficiency in a cold spot cannot be supplied in this way because the time is too short and most dielectric bodies are poor heat conductors. The principal advantage of high frequency heating are speed and economy of energy and these would both be lost if the heating interval were prolonged sufficiently to heat the cold spots by heat conduction from the hotter zones. Also, the temperature of the hot zones might then need to be so high as to damage the wood during an extended heating interval.

The general object of the present invention is therefore to provide an improved method of high

2

frequency heating to overcome the disadvantages pointed out and accomplish substantially uniform heating of a dielectric material.

Another object is to provide a method of heating dielectric bodies in a high frequency field to produce a substantially uniform heating effect regardless of the size of the body or the frequency of the voltage wave.

Another object is to provide a method of and 10 means for preventing permanent fixed nodal points in standing waves in high frequency heating circuits.

A specific object is to utilize frequency modulation 15 to shift the position of standing waves in a high frequency heating circuit.

In carrying out the objects of the invention the occurrence of cold spots at fixed points in the dielectric body resulting from a standing wave is prevented by rapidly shifting the position of the 20 voltage nodal points with respect to the dielectric body. This is conveniently accomplished by frequency modulation of the voltage wave. As the frequency changes, the wave length changes and the nodal points move accordingly so that no 25 point on the conductor is continuously at minimum potential. Inasmuch as the heating effect in the dielectric body varies with voltage intensity from point to point, the variations in heating effect are thereby attenuated to achieve a satisfactory degree of uniformity of heating throughout the whole body. For reasons which will become apparent as the description proceeds in connection with the accompanying drawings it is preferred to make the average frequency sufficiently high to produce a number of complete 30 cycles within the work. It is also desirable to make the modulating frequency sufficiently high so that the time of one cycle is short with respect to the length of the heating interval.

40 In the drawings:

Figure 1 is a schematic representation of apparatus for practicing the method of the invention in connection with the gluing of plywood and the like in a press having a pair of insulated 45 electrodes to produce a single dielectric circuit through the work;

Figure 2 is a view similar to Figure 1 showing how the invention may be applied to a conventional press having grounded platens by inserting 50 an intermediate electrode in the press load to establish a pair of dielectric circuits through the work;

Figure 3 is a diagram showing the effect of frequency modulation on a standing wave in a high 55 frequency circuit; and

Figure 4 is a diagram showing the beneficial effect of frequency modulation in attenuating the variations in heating effects produced by a standing voltage wave in the electrodes shown in Figures 1 and 2.

In Figure 1 the numerals 1 and 2 designate mutually insulated electrodes of opposite polarity on opposite sides of a dielectric body 3 to be heated. These electrodes are connected by conductors 4 and 5 with a high frequency oscillator which is herein designated as a frequency modulated oscillator in order to carry out the principles of the invention.

Figure 2 illustrates the application of high frequency heating to a conventional press of the type used for making plywood or for making scarf joints and the like wherein the upper and lower press platens 7 and 8 are utilized as electrodes on opposite sides of a press load of panels 3. Such platens are ordinarily grounded to the frame whereby they are electrically connected together as indicated by the wire 4a. The panels in the stack 3 contain a thermosetting glue which may be efficiently heated in a high frequency field to raise the temperature of the glue to cause it to set permanently and form a bond with the wood veneers or the plywood as the case may be. The press load 3 is thereby made up of two dielectric materials, one being the wood and the other being the glue films in the joints to be glued. It is desired to heat the glue films as uniformly as possible so that all the glue will be heated to its critical temperature without heating some of the glue to its temperature of decomposition and without causing damage to the wood. It is also desirable to accomplish the heat setting of the glue as quickly as possible to increase the output of the press and to reduce to a minimum the time of exposure of the wood to elevated drying temperatures. The entire heating interval is therefore not of sufficient duration to accomplish any effective attenuation of temperature variations in the glue in different parts of the stack, whereby a fairly high degree of uniformity of heating must be accomplished directly in the heating effect developed in the dielectric materials.

Since the platen electrodes 7 and 8 are already connected together through the frame of the press, a separate electrode 9 is inserted in the middle of the stack 3 as shown, this electrode then being connected to the wire 5 from the oscillator. Two separate dielectric fields are thereby produced between the press platens 7 and 8, but in the subsequent analysis of the heating action only one of these fields will be considered as would be the case in Figure 1.

In Figure 3 the numeral 10 designates a coupling with a high frequency oscillator having a pair of conductors 11 and 12 extending therefrom, these parts being shown in phantom. If Figure 3 is referred, for example, to Figure 1, the conductor 11 would comprise the wire 4 and the electrode 1 extending to the length shown from the coupling 10. Similarly the conductor 12 comprises the wire 5 and electrode 2. The vertical line 13 is drawn through the coupling 10 to form with the line representing the conductor 12 the coordinate axes of a graph on which is drawn a voltage curve 14 of a standing wave in the output of the system. The superposition of the voltage curve 14 upon the phantom representation of the conductor 12 thereby illustrates the variations in potential from point to point produced by the standing wave in the conductor. The con-

ductors 11 and 12 constitute an open end antenna wherein a standing wave will have a loop or maximum potential at the open end thereof as indicated by the end 15 of the curve 14. Such a standing wave is formed at a fixed frequency if the length of the conductors 11 and 12 exceeds one-quarter wave length.

If the electrode 2 is itself approximately one-quarter wave length in its greatest dimension, a particularly bad condition exists because the standing wave then has a maximum value on one side of the press and minimum value on the other side of the press. With a fixed frequency, no amount of increase in the output would be effective in heating the low potential side of the press, except by heat transfer from the hot side.

In the example illustrated in Figure 3, the wave length is approximately equal to the width of the press platens, thereby developing maximum voltage in the standing wave at points 15, 16 and 17 and minimum voltage at the nodal points 18 and 19. The heating curve for such a standing wave is illustrated by the line 14a in Figure 4. Here the electrode or platen 2 is shown in phantom, and only that part of the circuit having an immediate effect upon the body to be heated is illustrated. Thus, the points of maximum and minimum heating effect are designated by the same reference characters used on the voltage curve with the subscript a added. The heating curve 14a takes the form of a rectified voltage curve.

It will be apparent that if higher fixed frequencies are used, the number of nodal points will increase and the effect of each one will be less pronounced because it will influence a smaller area or volume of the body to be heated, but such points nevertheless represent cold spots into which the heat cannot flow fast enough to raise the temperature to the required critical value in the time allowed without greatly overheating the hot spots 15a, 16a and 17a.

The present solution to the problem is therefore to shift the nodal points back and forth on the electrode so that within the heating interval 45 heat will be applied with more uniformity to all parts of the dielectric body. Since the point 15 cannot be shifted without mechanically changing the length of the conductor it is preferred to shift the nodal points by changing the wave length which is easily accomplished by providing the oscillator with frequency modulation.

If the frequency is doubled the standing voltage curve appears as the broken line curve 20 having maxima at 15, 21, 22, 23, 17 and 24. Nodes of minimum voltage are then formed at 25, 26, 27, 28 and 29. With a shift to double frequency, the heating loops and nodes are moved as shown by the broken line curve 20a in Figure 4. The node 18a is moved to the point 25, the node 19a is moved to the point 26, etc. Likewise the loop or maximum 18a is moved to the point 21a which is at the former nodal position 18a. Likewise another loop or maximum then appears at the point 23a coincident with the position of the former node 19a. Thus it is seen that if the frequency is at least doubled the original nodes become maxima and the new nodes fall at points which have previously received a substantial heating effect. The modulating action, of course, moves the loops and nodes progressively and continuously between certain predetermined limits depending upon the extent of movement desired. For a ratio of frequency limits of 1 to 2 the curves 14 and 14a may be considered as representing

the lower frequency limit and the curves 20 and 20a as representing the upper frequency limit. These frequencies produce one wave length across plate electrodes of the length shown in Figures 1 and 2 at the lower frequency limit and two wave lengths across the electrodes at the higher frequency limit, the average frequency producing one and one-half wave lengths.

However, the curves shown in Figures 3 and 4 are merely diagrammatic and do not represent the actual number of wave lengths desired across the width of the platen. As previously mentioned, it is desired in practice to employ a frequency range having an average value to produce a number, such as ten or more, wave lengths across the width of the body to be heated instead of only one and one-half wave lengths as shown in Figure 3 for convenience of illustration. The number of wave lengths across the body is of course not critical as long as this condition is satisfied. Any degree of modulation of this average wave length is helpful, but, as explained above, the modulation is most effective if the upper and lower limit frequencies have at least a two to one ratio. The modulation frequency has no critical value except as previously stated that the time of one modulation cycle should be short in relation to the duration of the heat treatment period, in order to shift the nodal points repeatedly during the treatment.

The invention is, of course, not limited to the heating of glue nor to applications involving press platens. It is of general application to all forms of dielectric field heating where it is desired to employ electrical frequencies high enough to produce standing waves in the electrodes employed.

Having now described my invention and in what manner the same may be used, what I claim as new and desire to protect by Letters Patent is:

1. In high frequency electrical energy heating employing electrodes and conductors having a length which is appreciable compared to the wave length of said energy and normally subject to a standing wave having a nodal point in said electrodes whereby the heating effect varies along said electrodes in accordance with the position of said wave, the method of attenuating variations in said heating effect in a heating period comprising continuously varying the frequency of the source of said energy in a modulating cycle 50 which is short in relation to the heating period

and between limits in which the highest frequency is approximately double the lowest frequency to place wave crests at the highest frequency repeatedly in positions occupied by the nodal points at the lowest frequency.

2. The method of heating dielectric material between electrodes in a heating period by the use of high frequency electrical energy where the electrodes have a length which is appreciable compared to the wave length of said energy and normally subject to standing waves having at least one nodal point in the electrodes, comprising applying a high frequency potential to said electrodes to produce said standing wave, and varying the frequency of the source of said potential rapidly in relation to the length of the heating period and sufficiently to move the crests and nodes of said wave back and forth to cause a nodal point and wave crest to fall repeatedly at the same point in said electrodes at different times in a heating period, to attenuate variations in the heating effect produced by the standing wave.

3. In a high frequency electrical energy heating system having electrodes of a length which is appreciable compared to the wave length of the energy employed and normally subject to standing waves having at least one nodal point in said electrodes at which a minimum heating effect is produced, a frequency modulated oscillator for producing said standing wave, the frequency of said oscillator being controlled to vary the frequency between limits having the approximate ratio of 1 to 2 to place the nodal points of the wave at the lowest frequency in positions occupied by wave crests at the highest frequency.
